UNITED STATES PATENT OFFICE.

JOHN F. MAKOWSKI, OF STOCKTON, CALIFORNIA, ASSIGNOR TO CALIFORNIA CEDAR PRODUCTS COMPANY, OF STOCKTON, CALIFORNIA.

PLASTER LATH.

Continuation of application Serial No. 608,595, filed December 23, 1922. This application filed March 22, 1924. Serial No. 701,057.

To all whom it may concern:

Be it known that I, JOHN F. MAKOWSKI, a citizen of the United States, residing at Stockton, county of San Joaquin, State of California, have invented certain new and useful Improvements in Plaster Laths; and I do declare the following to be a full, clear, and exact description of the same, reference being had to the accompanying drawings, 10 and to the characters of reference marked thereon, which form a part of this application.

This invention relates to the building art and particularly to plaster wall construction, this application being a continuation 15 of my application, Serial No. 608,595, filed December 23, 1922.

The main object of the invention is to produce a lath or plaster board to be used 20 as a substitute for wooden or metal lath heretofore commonly used in the plastering art.

The ideal plaster lath is one which can be manufactured at a reasonable price; will 25 present a smooth even surface; will function as an efficient bond for the plaster or other plastic material; and which will not be subject to expansion, contraction, cracking or sagging, so that the plastered surface 30 will remain smooth and true without cracking or flaking off.

Much effort has been put forward by inventors to this end and so far it has been found that the one coming nearest to giving 35 the desired result has been a plaster lath having as its base a smooth sheet of wall board of that type wherein a center core of gypsum plaster, and a filler such as sawdust or the like, is interposed between and adhered to surface sheets of strong paper such as chip board or the like. With this smooth board as a base many different types of mechanical plaster keys or bonds have been formed on its face such as protuberances 40 projecting therefrom, or recesses, depressions or perforations formed therein.

There has been one thing however which has acted to cause this type of plaster lath to be more or less unsatisfactory and that 50 is the fact that in many cases when the wet plaster is applied over the same the moisture therein is apt to saturate the paper covering of the wall board, or its plastic core, before the plaster has had time to dry and

harden and set. When this occurs the surface paper loses its tensile strength and is weakened to such an extent that it may tear or sag, or the plaster core may become soggy to such an extent that it will warp and sag the whole board. These things of course cause the outer plaster surface to be wavy or to sag, break, or flake off, which of course ruins its appearance.

I have attacked the problem of overcoming this defect in the production of my improved plaster lath as herein disclosed and I claim to have solved it and to have perfected a plaster lath which will have the several advantages derived from the use of wall board of the type above set forth and with none of the disadvantages of the kind described.

The thing which I conceived to be necessary to make the lath a success was to keep the moisture of the plaster out of the base board while the plaster was drying, hardening and setting and at the same time provide a perfect bond between the two at all times.

To keep the moisture out during the time noted I conceived of the idea of treating the surface paper with an element which would retard the permeation of moisture therethrough for a period of time sufficient to allow the outer plastered surface to dry, harden and set. This would hold the moisture not only out of the paper but would also keep it out of the plastic core of the wall board if I maintained the surface paper in smooth unbroken condition. As most of the previously known plaster laths of this type have the mechanical key or bond for the plaster formed thereon by breaking the paper to make depressions or protuberances, I was compelled, in order to render the use of my treated paper practical, to devise a key or bond which would be entirely outside of the unbroken and treated surface paper of the base and yet adhered thereto with a tenacity to carry the weight of the plaster 100 to be adhered thereto.

The figure on the drawings is a perspective view of a section of my improved plaster lath showing plaster adhered to a portion thereof.

Referring now more particularly to the characters of reference on the drawings, the numeral 1 designates the internal core of the

wall board base which core is made preferably of gypsum plaster and a filler element such as sawdust or the like, the surface sheets 2 and 3 being united in superficial contact therewith in accordance with the process set forth in my co-pending application for patent, Serial No. 682,483.

When this type of wall board is being manufactured for use as a plaster lath in accordance with the present invention at least one of the surface sheets 2 or 3 is treated to render it capable of retarding the permeation of moisture therethrough for a period of time sufficient to allow the surface coating of plaster 6, to be adhered thereto, to dry, harden and set without the moisture therein saturating the paper or plastic core. This treatment may be by incorporation of the element itself in the paper in manufacture or by sizing after the board is made. The element used will be rosin or other known retardents.

The paper being thus treated the next necessary step is to arrange a mechanical key 25 on the outer surface thereof. Preferably I use finely divided mineral fragments 4 adhered to the paper by an adhesive which must of course be essentially insoluble in order that the same will be also unaffected 30 by the moisture in the plaster 6 when the same is first adhered thereto.

I have done vast experimenting to find the proper adhesive element for this last noted purpose and have several co-pending 35 applications covering same, each of them having certain other properties essential to the manufacture of a commercially successful lath. For the purpose of this application I disclose this adhesive shown on the drawing at 5, as a composition of casein, lime and china clay or any similar diatomaceous earth. In this composition the casein is the insoluble element, the lime acting as a temporary solvent for the same, 45 and the diatomaceous earth giving the necessary body to the composition.

Such an insoluble adhesive composition could also be so compounded as to act to treat the surface paper of the wall board 50 to retard permeation thereof by moisture. When this was done the paper when first adhered to the plastic core would not need to be anything but plain untreated chip board or the like. A larger quantity of the 55 adhesive composition would then have to be used however so that it could thoroughly impregnate the paper and at the same time have body enough to allow the mineral fragments to tenaciously adhere thereto or in 60 itself be of a thickness necessary to retard the permeation of moisture, through to the paper, for the requisite period of time herein indicated.

I must lay stress on the fact that the 65 adhesive between the mechanical bond and

the surface sheet of paper of the base board must be insoluble in any event, otherwise when the wet plaster was spread over the lath this adhesive would dissolve and slide off the surface and the entire utility of the 70 lath would be destroyed.

While I have herein indicated the mechanical key or bond surface as preferably provided by the finely divided gravel still in practice such may be provided in perhaps many other ways. It might even, for instance, be provided by placing a relatively thick coat of insoluble material over the surface of the base board and then scarifying it to provide a rough surface to act as 80 such key or bond.

From the foregoing description it will appear that I have produced a plaster lath which will permit of the use of a wall board base, with its many advantages, at 85 the same time avoiding the disadvantages heretofore encountered.

Having thus described my invention what I claim as new and useful and desire to secure by Letters Patent is:

1. A plaster lath comprising a plastic base united to a surface sheet of paper or the like in superficial contact therewith, such paper being treated to retard its permeation by moisture, and a plaster key or bond arranged on the outer face of the paper.

2. A plaster lath comprising a plastic base united to an unbroken surface sheet of paper or the like in superficial contact therewith, such paper being treated to retard its permeation by moisture, and a plaster key or bond arranged on the outer face of the paper.

3. A plaster lath comprising a plastic base united to a surface sheet of paper or the like in superficial contact therewith, such paper being treated to retard its permeation by moisture, an insoluble coating on the outer surface of the paper, and a plaster key or bond formed in such insoluble coating.

4. A plaster lath comprising a plastic base united to a surface sheet of paper or the like in superficial contact therewith, such paper being treated to retard its permeation by moisture, an insoluble coating on the outer surface of the paper, and finely divided material adhered to such coating to form a plaster bond or key.

5. A plaster lath comprising a plastic base united to a surface sheet of paper or the like in superficial contact therewith, and a plaster key or bond formed on the outer surface of such sheet of paper, the paper being treated to retard its permeation by moisture, from the plaster applied to such key or bond, for the period of time required for such plaster to harden and set.

6. A plaster lath comprising a plastic

base united to a surface sheet of paper or the like in superficial contact therewith, and a plaster key or bond formed on the outer surface of such sheet of paper, and means whereby, when plaster is applied thereto, the moisture in such plaster will be excluded from permeating the paper or plastic base.

7. A plaster lath comprising a plastic base united to a surface sheet of paper in

superficial contact therewith, a coating of 10 surfacing material on the outer face of such paper sheet consisting essentially of casein and a body material, and a plaster key or bond formed in such coating.

In testimony whereof I affix my signature.

JOHN F. MAKOWSKI.
